COMBINATION TONGUE AND
BOX BUCKLE

William Ewanyk, Norwalk, Conn.

Application May 25, 1949, Serial No. 95,200

7 Claims. (Cl. 24—175)

1

This invention relates to buckles for belts and the like.

As it is well known in this art, there are two types of belt buckles now in use, one being the so-called tongue buckle wherein a tongue pivoted in a frame is pushed through a hole in the belt and that way the belt is secured, as will be obvious. The other type is the so-called box buckle in which the belt is pulled through a box-like structure open at both ends and secured therein in any suitable manner, the exposed front or top of the box being adapted to be used for ornaments, initials, and the like. The drawback of this second type of buckle is that the belt is never reliably secured, while the drawback of the tongue type buckle otherwise reliably secured, is that it is unsightly.

The main object of my invention is to provide a belt buckle which will combine the advantages of both types, whereby the belt will be reliably secured by a tongue, but, at the same time, the buckle will have the appearance of a box buckle, having a cover or top thereon, with ornaments, initials, or the like, displayed on it. With my invention the belt will be absolutely secured by a tongue, but at the same time, it will have the ornamental aesthetic appearance of a box buckle.

Another object of my invention is to provide a device of the mentioned character, which may be opened in a comparatively easy manner, exerting only a reasonable force on its cover.

Still a further object of this invention is to provide a belt buckle of the character indicated wherein the usual frame and tongue will be employed, but a box buckle imitation top or cover will be pivoted at one side of said frame whereby the belt will be adapted to be locked in its adjusted position by the tongue, and the pressure of the tongue, and of the belt itself, on said pivoted cover will keep the same in a yieldingly locked position.

Still another object of this invention is to provide a device as characterized hereinbefore, wherein the ornamental box cover may be opened comparatively easily against said pressure by turning the same, whereupon the belt may be unhooked from the tongue as usual.

Still further objects of this invention will be apparent as the specification of the same proceeds, or will be pointed out therein, and, among others, I may mention: to provide a device of the many advantages indicated, which still will be simple in construction, inexpensive to manufacture, aesthetic in appearance, and efficient and reliable in operation and use.

2

In the drawings forming a part of my invention and accompanying the same:

- Fig. 1 is a fragmentary front view of a man wearing the belt embodying my invention;
5 Fig. 2 is a perspective view of the preferred embodiment of my novel combination belt buckle, portions of the same being broken away for clearer view;
Fig. 3 is a sectional view of my device showing
10 the free end of the belt by which the same is adjusted and locked through said buckle;
Fig. 4 is another sectional view showing my device applied to a belt in adjusted and closed position, and
15 Fig. 5 is a fragmentary view showing a pivoted cover of my device and the end of a frame receiving the same.

Referring now to the drawings more in detail by characters of reference, my novel combination tongue and box belt buckle 10, is composed of two main elements, a frame member 11 and a cover 12 pivoted thereon, as will be more fully explained hereinafter. The frame member 11 is formed of two sides 13 and 14, a belt receiving end member 15, and an opposite end member generally indicated by the numeral 16, and in the embodiment shown being composed of two pins 17 and 18 on which the cover 12 is pivoted.

A tongue, generally indicated by the numeral 19, is pivoted at about the center of the end member 15, and a stationary end 20 of the belt 21 is secured on said end member, as it is well known in this art, permitting a swinging motion of the tongue 19, which, if desired, may be pivoted on a special pin portion of the end member 15.

The cover member 12 is in the form of a plate appropriately curved, if desired, to follow a similar curvature in the frame member and generally in the body of the wearer, and at its inner end it has a sleeve 22 formed thereof. Said sleeve has a central portion 23 preferably not entirely closed, having an inner free edge 24 normally underneath the cover plate 12 and concealed by it when the buckle is closed. It will be obvious that said sleeve, and the plate cover 12 of which it is formed may swing on the pins 17 and 18.

The tongue 19 may also be appropriately curved as shown in the drawings, and will have a hook-shaped outer or free end 27. Belt 21 on which my buckle is employed will have a free adjustable end, generally indicated by the numeral 28, provided with the usual spaced apart holes 29.

The operation and use of my device will be as follows: When the wearer desires to adjust the

belt, the free end 28 thereof will be pulled through the frame underneath the sleeve portion 23 until a desired hole 29 will be within the frame, whereupon the tongue 19 will be passed therethrough, as it is usual with tongue buckles. The free end 28 of the belt then will be placed smoothly over the frame member 11 of the buckle and the secured other end 20 of the belt 21, as also is usual and will be understood.

The tightening of the belt and securing the same by the tongue 19, however, will press the tongue inwardly on its pivot on the end frame member 15, as indicated by the arrow 30, by the stress in the belt and will press said tongue strongly in the direction of arrow 30, and will cause its hooked end 27 to engage the inner edge 24 of the sleeve portion 23, thereby causing the cover plate 12 to close upon the frame and tongue, as has been indicated hereinbefore, thereby concealing said construction and giving my buckle 20 the appearance of an ornamental box buckle.

As will be understood, such an action may be aided by the wearer himself by simply pressing the plate downwardly over the frame.

In the preferred embodiment, shown in the drawings, the hooked end 27 of the tongue in such a position of the cover plate 12, will engage the free inner edge 24 of the sleeve portion 23 and thereby keep said plate locked in its closed position.

I provide an additional locking and securing means for the closed position of cover 12, and for this purpose, an appropriate portion 31 of the sleeve 22 will be made flat.

Now, when the belt is adjusted, tightened, and secured in its tight position by the tongue 19, as has been described hereinbefore, and the cover plate 12 closed upon the buckle through such action, the tightness of the belt will exert an outward pressure on the flat portion 31 of the sleeve 22, as indicated by arrow 32, and, obviously, this pressure will also tend to keep the cover 12 in its closed position.

When it is desired to open the buckle, first the cover 12 will be pulled outwardly into an open position, which the wearer can easily do by exerting a comparatively small pulling force thereon. The forces exerted by the belt on the tongue 19 and on the flat portion 31 of the sleeve 22, will allow such a movement, after which the buckle may be opened like any other tongue buckle by pulling the free end 28 of the belt off of the tongue 19.

What I claim as new and want to protect by Letters Patent of the United States is:

1. In a belt buckle, the combination of a frame with two end members, one end member being adapted to have a stationary end of the belt secured thereon, the other free end of the belt to be passed underneath the opposite end member, said buckle also having a tongue pivoted on said first end member and adapted to be passed through a selected hole in said free end of the belt to adjustably secure the same, and a cover having a sleeve whereby it is pivoted on said second end member, the inner surface of said sleeve being flattened and a portion of said belt under said sleeve exerting an outward pressure on said flat surface sleeve the flat outer surface of it being adapted to be outwardly pressed by the portion when the tongue is engaged by said free belt end and the belt is tightened, the belt thereby holding said cover in a position closed over said frame and said tongue.

2. In a belt buckle, a frame having two sides

and a cross bar at one end registering spaced apart pins projecting inwardly and opposingly from the other ends of the respective sides of the frame, a tongue pivoted on said cross bar, a sleeve pivoted on said pins, and a cover for the device carried by said sleeve, said sleeve having an open portion between said two pins and the end of said tongue being adapted to engage and press on the lower edge of said open part of the sleeve, said tongue being shorter than the distance between said cross bar and said pins whereby its end will not engage any other parts of the sleeve but said free edge, said tongue being adapted to keep said cover in a position closed over said frame when the buckle is closed on a belt and the tongue is engaged by the free end portion thereof.

3. In a belt buckle, the combination of a frame with two end members, one end member being adapted to have a stationary end of the belt secured thereon, the other, free, end of the belt to be passed underneath the opposite end member, said buckle also having a tongue pivoted on said first end member and adapted to be passed through a selected hole in said free end of the belt to adjustably secure the same, and a cover having a sleeve whereby it is pivoted on said second end member, an open portion for said sleeve with a free edge underneath said cover, the outer free end of said tongue being adapted to press on the edge of said open sleeve portion when the tongue is engaged by said free belt end and thereby hold said cover in a position closed over said frame and said tongue, said free end of the tongue, however, not being long enough to reach any portion of said second member and to press thereon, the body of said tongue being concave to aid the pulling force of the belt thereon towards closing the free buckle end on said sleeve, said free end being inwardly curved to a hook to better engage the free edge in said sleeve.

4. In a belt buckle, the combination of a frame with two end members, one end member being adapted to have a stationary end of the belt secured thereon, the other, free end of the belt to be passed underneath the opposite end member, said buckle also having a tongue pivoted on said first end member and adapted to be passed through a selected hole in said free end of the belt to adjustably secure the same, and a cover having a sleeve whereby it is pivoted on said second end member, an open portion for said sleeve with a free edge underneath said cover, the outer free end of said tongue being adapted to press on the edge of said open sleeve portion when the tongue is engaged by said free belt end and thereby hold said cover in a position closed over said frame and said tongue, said free end of the tongue, however, not being long enough to reach any portion of said second member and to press thereon, the body of said tongue being concave to aid the pulling force of the belt thereon towards closing the free buckle end on said sleeve, said free end being inwardly curved to a hook to better engage the free edge in said sleeve.

5. In a belt buckle, the combination of a frame with two end members, one end member being adapted to have a stationary end of the belt secured thereon, said belt having a second free end adapted to be passed underneath the opposite end member, said buckle also having a tongue pivoted on said first end member and adapted to be passed through a selected hole in said free

end of the belt to adjustably secure the same, and a cover having a sleeve whereby it is pivoted on said second end member, said sleeve having a central portion provided with a free edge, the free end of said tongue being adapted to be pressed on said free edge of said sleeve when the belt is tightened thereby exerting a force on the same designed to keep said cover in a closed position, the inner surface of said sleeve being flattened and a portion of said belt under said sleeve exerting an outward pressure on said flat surface, when the tongue is engaged by said free belt end and the belt is tightened, and the belt thereby holding said cover in a position closed over said frame and said tongue.

6. In a belt buckle, the combination of a frame with two end members, one end member being adapted to have a stationary end of the belt secured thereon, said belt having a second free end adapted to be passed underneath the opposite end member, said buckle also having a tongue pivoted on said first end member and adapted to be passed through a selected hole in said free end of the belt to adjustably secure the same, and a cover having a sleeve whereby it is pivoted on said second end member, said sleeve having a central portion provided with a free edge, the free end of said tongue being adapted to be pressed on said free edge of said sleeve when the belt is tightened thereby exerting a force on the same, designed to keep said cover in a closed position, the body of said tongue being concave to aid the pulling force on the belt thereon towards closing the free tongue end on said sleeve, said free tongue end being inwardly curved to a hook to better engage said sleeve.

7. In a belt buckle, the combination of a frame

with two end members, one, the first, end member being adapted to have a stationary end of the belt secured thereon, the other, free, end of the belt to be passed underneath the said second end member, said buckle also having a tongue pivoted on said first end member and adapted to be passed through a selected hole in said free end of the belt to adjustably secure the same, and a cover having a sleeve whereby it is pivoted on said second end member, an open portion for said sleeve with a free edge underneath said cover, the outer free end of said tongue being adapted to press on the edge of said open sleeve portion when the tongue is engaged by said free belt end and thereby hold said cover in a position closed over said frame and said tongue, said free end of the tongue, however, not being long enough to reach any portion of said second end member and to press thereon.
